(57) **CLAIM**

The ornamental design for a control module for attachment to a lighting fixture, as shown and described.

DESCRIPTION

FIG. 1 is a perspective view of a control module for attachment to a lighting fixture;

FIG. 2 is a side view of a control module for attachment to a lighting fixture;

FIG. 3 is a side view of a control module for attachment to a lighting fixture;

FIG. 4 is a back view of a control module for attachment to a lighting fixture;

FIG. 5 is a front view of a control module for attachment to a lighting fixture;

FIG. 6 is a top view of a control module for attachment to a lighting fixture; and,

FIG. 7 is a bottom view of a control module for attachment to a lighting fixture.

In the drawings, the broken lines depict environmental subject matter only and form no part of the claimed design.
